UNITED STATES PATENT OFFICE.

ELI ANDERSON, OF CARPENTERSVILLE, INDIANA.

STRAW-STACKER.

SPECIFICATION forming part of Letters Patent No. 275,453, dated April 10, 1883.

Application filed December 23, 1882. (No model.)

To all whom it may concern:

Be it known that I, ELI ANDERSON, a citizen of the United States, residing at Carpentersville, in the county of Putnam and State of Indiana, have invented a new and useful Straw-Stacker, of which the following is a specification, reference being had to the accompanying drawings.

This invention relates to machines for stacking straw; and it consists in certain improvements in the construction of the same, which will be hereinafter fully described, and particularly pointed out in the claims.

In the drawings hereto annexed, Figure 1 is a perspective view, showing the machine extended and in position for operation. Fig. 2 is a longitudinal vertical sectional view, showing the machine folded for transportation. Fig. 3 is a vertical transverse sectional view; and Fig. 4 is a detail view, in side elevation, of part of the adjusting mechanism.

The same or corresponding parts in the several figures are denoted by the same letters of reference.

The transporting-frame of my improved straw-stacker consists mainly of a strong axle mounted upon wheels B B, and having the forwardly-extending tongue or coupling-bar C. Upon the axle, which is denoted by letter A, is secured a plate, D, having a forwardly-extending wing, E, which is firmly and permanently bolted upon the rear end of the tongue or coupling-bar. The plate D, which is fitted on top of the axle, is secured to the latter detachably by means of bolts and nuts F G, as shown. The ends of plate D have rearwardly-projecting arms or lugs H H.

Mounted centrally upon the plate D is a vertical shaft or upright, I, upon which is secured, by means of a set-screw, J, a sleeve, K, having a laterally-projecting arm or bracket, L, having bearings for a shaft, M, carrying at its outer end a band-wheel or pulley, N, and at its inner end a pinion or bevel gear, O, meshing with a gear-wheel, P, formed upon or attached to the under side of a drum or pulley, Q, mounted upon the vertical shaft or upright I, and having an annular downwardly-projecting flange, R, bearing upon the arm or bracket L, upon which the drum or pulley Q is thus supported. The said drum or pulley is pro-

vided at its lower end, above its toothed portion, with a flange, S. Another corresponding flange, T, is formed upon a sleeve, U, secured upon the shaft I, above the said drum, by means of a set-screw, V. The said flanges serve to confine the driving-belt W upon the pulley, and by the upper flange and sleeve, which, as shown, are stationary upon the shaft, the pulley is held in position, and its lower toothed portion kept in gear with the pinion O.

X is a cylindrical socket secured upon the upper end of the shaft I by means of a set-screw, Y. The said socket is provided with laterally-projecting arms ZZ, the outer ends of which have uprights A' A', provided at their upper ends with bearings for a transverse shaft, A², one end of which has a pulley, B², connected by a belt, C², with the pulley N upon the shaft M.

D² is the trough or box forming the body of the straw-carrier, and consisting of two sections, E² E³, suitably hinged together in such a manner as to be capable of folding one over the other when the device is not in use. The front or lower section of the carrier is hinged, as shown, upon the transverse shaft A². A suitable carrying belt or apron is provided, which runs upon pulleys or guides upon the shaft A², and upon a shaft, F², mounted at the rear end of the upper or rear section of the stacker.

G² is a forked or U-shaped bracket hinged or pivoted to the under side of the front section, E², of the stacker, and terminating in a segmental toothed arm or rack, H².

I² is a bracket projecting rearwardly from the sleeve K, and provided with upwardly-projecting arms J², forming bearings for a transverse shaft, K², having a pinion, L², engaging the rack H², which slides between the arms J². The shaft K² is also provided with a crank, M², by which it may be conveniently turned, and it has a ratchet-wheel, N², engaging a pawl or detent, O², pivoted to the side of one of the arms J², for the purpose of preventing the shaft from turning back after being adjusted to the desired position.

The operation of my invention will be readily understood from the foregoing description, taken in connection with the drawings hereto annexed. The stacker is extended for opera-

tion to the position shown in Fig. 1 of the drawings. By turning the crank of shaft K² the carrier may be raised or lowered to any desired elevation. Motion is communicated from any suitable machinery or motive power, by means of the belt or band W, to the drum or pulley Q, which, through the gear-wheel P, pinion O, pulley N, and belt C², communicates motion to the shaft A² of the carrying-apron. 10 By loosening the set-screws J and Y, the carrier may be turned upon the shaft I to any desired position.

When the machine is to be moved from one place to another it may be folded, as shown in Fig. 2, by detaching the bolts and nuts F G, and tilting the hinged plate D, with the shaft I and its attachments, forwardly until the said shaft rests between the arms A³ A³ of a bracket, B³, secured, as shown, to the coupling-bar. The carrier, which has been previously folded, will then be held securely between the arms or lugs H H of the plate D.

I claim as my invention and desire to secure by Letters Patent of the United States—

15 1. In a straw-stacker, the combination of the transporting frame or axle, a plate, D, bolted detachably thereto, the upright or shaft I, secured to said plate, the folding carrier mounted upon said shaft or upright, and the wing E, 20 hinged to plate D and attached permanently to the transporting-frame, as set forth.

2. In a straw-stacker, the combination of the transporting-frame, the shaft or upright mounted upon the same, the sleeve secured by

a set-screw upon the said shaft and having laterally-projecting arms, a shaft journaled in the latter, a band-wheel, a belt connecting said band-wheel with the carrier-shaft, a pinion at the inner end of said shaft, and a driving-pulley journaled upon the vertical shaft and provided with teeth meshing with said pinion, as set forth.

3. The combination, with the sleeve mounted upon the vertical shaft, the shaft journaled in the laterally-projecting arm of the same, and a pinion on said shaft, of the flanged pulley mounted upon said vertical shaft and having a downwardly-projecting annular flange, by which it is supported upon the said sleeve, substantially as set forth.

4. The combination of the transporting-frame, the vertical shaft or upright, the carrier swiveled to the upper end of the latter, a hinged forked bracket terminating in a curved rack, a sleeve mounted upon the said upright and provided with a rearwardly-extending bracket, a pinion engaging said rack, and means, substantially as described, for communicating motion to the apron of the carrier, as set forth.

In testimony that I claim the foregoing as my own I have hereto affixed my signature in presence of two witnesses.

ELI ANDERSON.
